PORATION OF VIRGINIA

DATING AND NUMBERING MECHANISM

Application filed October 12, 1928. Serial No. 312,007.

This invention relates to combined dating and numbering mechanisms for use in connection with rotary printing presses.

An object of this invention is improved means for changing each of said mechanisms at predetermined intervals in the cycle of operations of the printing press with which they are used.

According to this invention the dating and numbering mechanisms are mounted on a rotating cylinder co-operating with an impression cylinder. The dating and numbering cylinder is provided with two shafts coaxial therewith, one of which is operatively connected to the dating mechanism and the other of which is operatively connected with the numbering mechanism, so that angular movement of the shafts relative to the cylinder produces changes in the dating and numbering mechanisms. Means are provided for actuating the shafts at predetermined intervals of rotation. By means of this arrangement sets of envelopes, or the like, bearing identifying dates and numbers may be automatically printed.

Other objects, novel features and advantages of this invention will be apparent from the following specification and accompanying drawings, wherein—

Fig. 1 is a vertical section through the dating and numbering cylinder embodying the invention;

Fig. 2 is a section on the line 2—2 of Fig. 1;

Fig. 3 is a section on the line 3—3 of Fig. 1;

Fig. 4 is a partial side elevation of a printing press equipped with the cylinder disclosed in Fig. 1;

Fig. 5 is a fragmentary end view of the cylinder showing a part of the actuating means for the numbering mechanism;

Fig. 6 is a perspective view of another part of the actuating means for the numbering mechanism, and

Fig. 7 is a view of the opposite end of the cylinder showing part of the actuating means for the dating mechanism.

The dating and numbering cylinder comprises a hollow axle 10, upon which are mounted the collars 11, between which extends a shield 12, the ends of which fit in

notches in the collars and are bent over against the outside faces thereof, bolts 13 being provided to fasten the ends of the shield to the collars. The axle 10 is journaled in bearings 14 and has a gear 15 fastened to one end and a collar 16 fastened to the other end.

In one end of the axle 10 there is rotatably mounted a shaft 17 to the inner end of which is attached a radially extending arm 18 projecting through a slot 19 in axle 10. A ratchet arm 20, having a notch 20a, is keyed to the outer end of the shaft 17 and is held in place by a washer 21 and nut 21a. A ratchet wheel 22 is rotatably mounted on washer 21 and is held against axial movement by the cleat 23 carried by the gear 15.

A pawl 24 is pivotally carried at the end of an arm 24a pivotally supported on the gear 15, and is adapted to engage the teeth 25 of the ratchet wheel 22, and, under certain conditions, to project into the notch 20a of the arm 20. A spring 26 having one end attached to the pawl and the other end to a stop 26a carried by the gear 15 for the lever 24a normally holds the pawl in the retracted position shown in Fig. 4. The roller 27 is supported by the frame of the printing press in position to be engaged by the arm 24a upon each rotation of the cylinder.

The engagement of the arm 24a with the roller 27 causes movement of the pawl to advance the ratchet wheel to the extent of a single tooth. The depth of the notches between the ratchet wheel teeth, with certain exceptions, is such as to prevent the pawl from projecting into the notch 20a, so that normally the pawl has no effect on the arm 20. One or more of the notches between the teeth are of sufficient depth that when the pawl enters these notches it also projects into the notch 20a, thereby moving the arm 20 slightly and causing corresponding angular movement of the shaft 17. In the particular embodiment disclosed, only one deep notch 22a is provided, but there may be as many deep notches as desired according to the intervals at which the arm 20 is to be actuated. If it is desired to actuate the arm 20 upon each rotation of the cylinder, the ratchet wheel 22 is removed and

the pawl 24 permitted to engage the notch 20 α at each operation of the arm 24a.

5 A shaft 30 is rotatably supported by and extends between the collars 11. An arm 31 is affixed to this shaft and its free end is connected to the free end of the arm 18 by a link 32. A pair of numbering mechanisms 33 are rotatably mounted on a shaft 34 extending between the collars 11 and rotatably supported thereby. These numbering mechanisms are actuated by oscillation of arms 35 supported by the shaft 34. The free ends of these arms are connected by links 36 with arms 37 fastened to the shaft 30.

10 When the pawl 25 is brought into engagement with the ratchet 20 to effect angular movement of the shaft 17 relative to the axle 10, the arm 18 is moved as indicated in Fig. 2. Likewise, through the medium of the link 32 and arm 31, the shaft 30 is rotated slightly, as indicated in Fig. 3. The arms 35 are caused to swing by the links 36 and arms 37, thus advancing by one the numbers of the numbering mechanism. A spring 28 is provided to 20 return the various elements just mentioned to their normal position after actuation, when the pawl 24 is retracted by its spring 26.

25 The arrangement of the arm 31 and link 32 and of the arms 35 and links 36 is such that the arms 35 move more slowly at the end of the operating stroke than at the start, thus preventing overthrow of the numbering mechanism.

30 In the opposite end of the axle 10 is rotatably mounted a shaft 40, at the inner end of which is provided a pinion 41. This pinion meshes with a pinion 42 carried by the collar 11 and extending through a slot in the axle 10. The pinion 42 in turn meshes with a pinion 43 keyed to the shaft 34. On the shaft 34, between the numbering mechanisms 33, is mounted a roller 44. An endless belt 45 passes around this roller, which is in driving engagement therewith, and also around other 35 guide rollers 46, supported by rods or shafts extending between the collars 11. Arms 46a, mounted on the axle 10, support one of the rods carrying the roller 46, and are angularly adjustable to vary the tension of the belt 45. 40 This belt is composed of a series of type-carrying links pivotally connected together and located below the printing surface, except at a single point where one link at a time is designed to cooperate with the impression 45 cylinder of the press.

45 The outer end of the shaft 40 is provided with a ratchet wheel 47, which is held in place by cleats 48. A pawl 49 is pivotally connected to the end of an arm 50, pivotally mounted on the collar 16. A spring 51 normally holds the pawl in retracted position. On the frame of the press is provided a roller 52, which is adapted to be engaged by the arm 50 upon each rotation of the cylinder to 55 move the pawl 49 into engagement with the

teeth of the ratchet wheel 47, thereby advancing the same to the extent of a single tooth. The arm 50 is provided with a stud 53, which, when the arm is actuated, engages the face of a tooth of the ratchet wheel to prevent overthrow thereof at high speed. The angular movement on the part of the shaft 40 is communicated by the gear train to the shaft 34, angular movement of which advances the belt 45 to the extent of a single link. Thus, upon each rotation of the cylinder, the dating mechanism is advanced a single step and a different date is printed upon each rotation of the cylinder.

60 The above described dating and numbering mechanism is particularly adapted for use in connection with the printing of church collection envelopes and the like, where envelopes are put out in sets, the envelopes of each set bearing the same identifying number and the successive envelopes being dated chronologically. Where the set contains 52 envelopes, the ratchet 25 is provided with 52 teeth and a single deep notch, so that the numbering mechanism is changed after one 65 complete cycle of the dating mechanism. The number of teeth in the ratchet wheel 25 and the number of deep notches may be varied as desired to meet different conditions.

70 Where it is desired to number envelopes successively, the ratchet wheel 25 may be omitted and the numbering mechanism caused to advance upon each rotation of the cylinder. Under such circumstances, it may be desirable to print the same date on all the envelopes, and this may be accomplished by 75 swinging back the roller 52, so that it does not actuate the arm 48.

80 It is, of course, apparent that various structural modifications may be made in the apparatus above described, without in any way departing from the spirit of the invention as defined in the appended claims.

85 We claim:—

1. In a device of the character described, a 90 cylinder, a movable printing mechanism mounted thereon, a shaft rotatably mounted in said cylinder co-axial thereof, means connecting said shaft and printing mechanism whereby rotary movement of the former relative to the cylinder effects movement of the latter, means for effecting rotary movement of said shaft upon rotation of said cylinder and means rotatable with said cylinder for periodically preventing operation of said 95 last named means.

100 2. In a device of the character described, a cylinder, a movable printing mechanism mounted thereon, a shaft rotatably mounted in said cylinder co-axial thereof, means connecting said shaft and printing mechanism whereby rotary movement of the former relative to the cylinder effects movement of the latter, a ratchet mounted on said shaft, a 105 pawl pivotally carried by said cylinder and 110

- operatively associated with said ratchet and means engageable by said pawl upon rotation of said cylinder.
3. In a device of the character described, a cylinder, a movable printing mechanism mounted thereon, a shaft rotatably mounted in said cylinder co-axial thereof, an arm extending radially from said shaft, linkage connecting said arm and printing mechanism for actuating the latter by the former, means for effecting rotary movement of said shaft upon rotation of said cylinder and means rotatable with said cylinder for periodically preventing operation of said last named means.
4. In a device of the character described, a cylinder, a movable printing mechanism mounted thereon, a shaft rotatably mounted in said cylinder co-axial thereof, an arm extending radially from said shaft, linkage connecting said arm and printing mechanism for actuating the latter by the former, a ratchet mounted on said shaft, a pawl pivotally carried by said cylinder and operatively associated with said ratchet and means engageable by said pawl upon rotation of said cylinder.
5. In a device of the character described, a cylinder, a movable printing mechanism mounted thereon, a shaft rotatably mounted in said cylinder co-axial thereof, means connecting said shaft and printing mechanism whereby rotary movement of the former relative to the cylinder effects movement of the latter, a ratchet wheel rotatably mounted on said shaft, a ratchet fixed to said shaft, a pawl adapted to engage the teeth of said ratchet wheel and ratchet, the notches between the teeth of the ratchet wheel with at least one exception being too shallow to permit the pawl to engage said ratchet and means engageable by said pawl upon rotation of said cylinder.
6. In a device of the character described, a cylinder, a movable printing mechanism mounted thereon, a shaft rotatably supported by said cylinder, means connecting said shaft and printing mechanism whereby rotary movement of the former relative to the cylinder effects movement of the latter, ratchet and pawl mechanism for effecting rotary movement of said shaft relative to said cylinder and means periodically to prevent operation of said ratchet and pawl mechanism.
7. In a device of the character described, a cylinder, a movable printing mechanism mounted thereon, a shaft rotatably supported by said cylinder, means connecting said shaft and printing mechanism whereby rotary movement of the former relative to the cylinder effects movement of the latter, ratchet and pawl mechanism for effecting rotary movement of the shaft relative to the cylinder, means to actuate said pawl and means to prevent excess movement of the printing mechanism.
8. In a device of the character described, a cylinder, a movable printing mechanism mounted thereon, an operating lever for said printing mechanism, a shaft rotatably mounted in said cylinder co-axial thereof, an arm carried by said shaft, linkage connecting said arm and lever whereby rotary movement of the shaft relative to the cylinder effects movement of said printing mechanism, ratchet and pawl mechanism for effecting rotary movement of said shaft relative to said cylinder, means to actuate said pawl upon rotation of said cylinder and means periodically to prevent operation of said ratchet and pawl mechanism.
9. In a device of the character described, a cylinder, a movable printing mechanism mounted thereon, a shaft rotatably mounted in said cylinder co-axial thereof, means connecting said shaft and printing mechanism whereby rotary movement of the former relative to the cylinder effects movement of the latter, ratchet and pawl mechanism for effecting rotary movement of the shaft relative to said cylinder, means to actuate said pawl upon rotation of said cylinder, and means on said pawl to engage said ratchet to prevent excess movement thereof.
10. In a device of the character described, a cylinder, a movable printing mechanism mounted thereon, a shaft rotatably mounted in said cylinder co-axial thereof, means connecting said shaft and printing mechanism whereby rotary movement of the former relative to the cylinder effects movement of the latter, a ratchet fixed to said shaft, a pawl adapted to engage said ratchet, means engageable by said pawl upon rotation of said cylinder, and means for periodically preventing engagement of said pawl with said ratchet.
11. In a device of the character described, a cylinder, a movable printing mechanism mounted thereon, a shaft rotatably mounted in said cylinder, means connecting said shaft and printing mechanism whereby rotary movement of the former relative to the cylinder effects movement of the latter, means for effecting rotary movement of said shaft upon rotation of said cylinder, and means for periodically preventing operation of said last named means.
12. In a device of the character described, a cylinder, a movable printing mechanism mounted thereon, a shaft rotatably mounted in said cylinder, an arm extending radially from said shaft, linkage connecting said arm and printing mechanism for actuating the latter by the former, means for effecting rotary movement of said shaft upon rotation of said cylinder, and means for periodically preventing operation of said last named means.

13. In a device of the character described, a cylinder, a movable printing mechanism mounted thereon, a shaft rotatably supported by said cylinder, an arm extending radially from said shaft, linkage connecting said arm and printing mechanism for actuating the latter by the former, a ratchet mounted on said shaft, a pawl pivotally mounted on said cylinder and being adapted to engage 10 said ratchet, and means for actuating said pawl upon rotation of said cylinder.

14. In a device of the character described, a cylinder, a movable printing mechanism mounted thereon, a shaft rotatably supported 15 by said cylinder, means connecting said shaft and printing mechanism whereby rotary movement of the former relative to the cylinder effects movement of the latter, a ratchet mounted on said shaft, a pawl pivoted to 20 said cylinder and being adapted to engage said ratchet, and means for actuating said ratchet upon rotation of said cylinder.

In testimony whereof, we have signed our names to this specification.

25. MONTGOMERY OSBORNE JONES.
